United States Patent Office

Des. 204,793
Patented May 17, 1966

204,793

LAMP

Raoul E. Rodriguez, 2521 N. Burling St., Chicago, Ill.

Filed May 3, 1965, Ser. No. 85,056

Term of patent 14 years

(Cl. D48—20)

Fig. 1.

Fig. 2.

Fig.3.

Fig.4.

Fig.5.

FIGURE 1 is a perspective view of a lamp embodying the features of this invention, with the illuminating head portion in horizontal position;

I claim:

The ornamental design for a lamp, substantially as shown and described.
